SCREENING APPARATUS

Filed Feb. 28, 1929

By
Watson E. Coleman

UNITED STATES PATENT OFFICE

WILLIAM J. GARRISON, OF RIDGWAY, PENNSYLVANIA

SCREENING APPARATUS

Application filed February 28, 1929. Serial No. 343,384.

This invention relates to improvements in screening apparatus for the removal of flat particles from any material, and more particularly to improvements in the construction 5 of apparatus for use in screening gravel.

An important object of the invention is to produce a structure which, with but slight modification of the screens of existing shaker tables, may be readily applied to the shaker 10 tables and will serve to separate objectionable thin and flat particles from any material being screened.

A further and more specific object of the 15 invention is to provide a screening structure in which these flats are separated from gravel in the ordinary process of screening and are passed longitudinally of the screen to a suitable discharge point.

A still further object of the invention is 20 the provision of a structure of this character in which the separating element or elements are adjustable to enable determination of the size of the flats which will be discharged from a given screen deck in single or multi 25 deck screening apparatus.

These and other objects I attain by the construction shown in the accompanying drawing, wherein for the purpose of illustration is shown a preferred embodiment of my in- 30 vention and wherein:—

Figure 1 is a fragmentary perspective view showing screening and separating apparatus constructed in accordance with my invention;

Figure 2 is a fragmentary side elevation 35 thereof;

Figure 3 is a fragmentary sectional view therethrough showing a slightly modified form of screen surface.

Referring now more particularly to the 40 drawing, the numeral 10 generally designates the side walls of a screen housing and 11 the woven screen unit which may be agitated in any suitable manner. These screens incline longitudinally and in accordance with my in- 45 vention, are centrally crowned either by placing the opposite sides of the screen at an angle to one another, as shown in Figure 1, or by arcuately curving the screen, as indicated in Figure 3. Extending over each screen are 50 supports 12, the ends of which are secured to

the separator walls, as indicated at 13. Each support 12 is provided with vertically extending portions 13^a overlying the screen in spaced relation thereto and in spaced relation to the side walls. These vertically extending 55 portions which are preferably provided by offsetting the support are abutted by longitudinal separator plates 14.

Each support 12 has formed in each of the vertically extending portions 13^a thereof an 60 angular slot 15 through which a bolt 16 carried by the associated plate extends.

It will be obvious that by loosening these bolts and shifting the plates longitudinally, the space of the lower edges of the plates 65 from the screen may be regulated.

The screens outwardly of the plates 14 are preferably constructed to prevent the passage of flats which pass under the separating plates 14 but will pass material smaller than 70 the flats thus separated. This is preferably accomplished by increasing the number of longitudinal wires or bars in the portions of the screen lying outwardly of the plates 14, thus decreasing the size of the mesh outwardly of the plates 14. This construction 75 is more clearly illustrated in Figures 1 and 3.

In the operation of the device, the material is discharged at the top end of the screen at the center thereof, and due to the crown of 80 the screen and the inclination thereof, said material tends to move transversely of the screen as it moves longitudinally thereof. This will cause the material to tend to bank up against the plates 14, and thin, flat particles in the material being treated will work out through the slots 19 under the lower edges of the plates 14 to the alleyways 17 provided between these plates 14 and the opposed walls 10 of the separator. The material passing 90 to the alleyways will pass longitudinally of the screen to a discharge outlet 18 which may, as illustrated, be disposed at the end of the separator.

It will be obvious that the particular means 95 of adjustment provided for the separator plates 14 and herein illustrated and the particular method employed for causing material to move transversely of the screen and come into coacting engagement with the sep- 100

arator plates 14 may be modified considerably without in any manner departing from the spirit of the invention and I accordingly do not limit myself thereto except as herein-after claimed.

5 I claim:—

1. In combination, a separator screen having at least a portion of its surface transversely inclined to cause travel of the material to one side thereof, plates supported above and extending longitudinally of the screen and having their lower edges in spaced relation to the screen, means limiting transverse movement of material upon the screen 10 after its passage beneath said plates, and means associated with the screen for preventing passage of material through the screen outwardly of said plates.

2. In combination, a separator screen having at least a portion of its surface transversely inclined to cause travel of the material to one side thereof, plates supported above and extending longitudinally of the screen and having their lower edges in spaced 15 relation to the screen, and means limiting transverse movement of material upon the screen after its passage beneath said plates, the mesh of said screen being decreased outwardly of said plates.

3. In combination, a separator screen having at least a portion of its surface transversely inclined to cause travel of the material to one side thereof, plates supported above and extending longitudinally of the 20 screen and having their lower edges in spaced relation to the screen, means limiting transverse movement of material upon the screen after its passage beneath said plates, means associated with the screen for preventing 25 passage of material through the screen outwardly of said plates, and means, for adjusting said plates toward and away from the screen.

4. In combination, a separator screen having at least a portion of its surface transversely inclined to cause travel of the material to one side thereof, plates supported above and extending longitudinally of the screen and having their lower edges in spaced 30 relation to the screen, means limiting transverse movement of material upon the screen after its passage beneath said plates, the mesh of said screen being decreased outwardly of said plates, and means for adjusting said plates toward and away from the screen.

5. In a separator, parallel side walls, a longitudinally inclined screen extending between said side walls and having its edges fixed thereto and supported therefrom, said 35 screen being transversely crowned, supports extending transversely over the screen and secured at their ends to said side walls, and plates extending downwardly from said supports, said plates being in slightly spaced relation to the side walls and having their lower edges in slightly spaced relation to the screen.

lower edges in slightly spaced relation to the screen.

6. In a separator, parallel side walls, a longitudinally inclined screen extending between said side walls and having its edges supported therefrom, said screen being transversely crowned, supports extending transversely over the screen and secured at their ends to said side walls, and plates extending downwardly from said supports, said plates being in slightly spaced relation to the side walls and having their lower edges in slightly spaced relation to the screen, the edges of the screen outwardly of said plates being formed to prevent passage of the coarser flat material therethrough.

7. In a separator, parallel side walls, a longitudinally inclined screen extending between said side walls and having its edges supported therefrom, said screen being transversely crowned, supports extending transversely over the screen and secured at their ends to said side walls, plates extending downwardly from said supports, said plates being in slightly spaced relation to the side walls and having their lower edges in slightly spaced relation to the screen, the edges of the screen outwardly of said plates being formed to prevent passage of the coarser flat material therethrough, and means for adjusting the plates toward and away from the screen.

In testimony whereof I hereunto affix my signature.

WILLIAM J. GARRISON.
